COMPOSITIONS AND METHODS OF TREATING
CONVULSANT SEIZURES

Arthur Berger, Skokie, and Edeltrant E. Borgaes, Chicago, Ill., assignors to Baxter Laboratories, Inc., Morton Grove, Ill., a corporation of Delaware
No Drawing. Filed Apr. 20, 1966, Ser. No. 543,809
11 Claims. (Cl. 167—65)

This case is a continuation-in-part of co-pending application Serial No. 336,614, filed January 9, 1964, now abandoned.

The present invention relates to the treatment of convulsant seizures in animals. More particularly, it relates to the use of certain derivatives of thiosemicarbazides which heretofore have not either been employed in or recognized as effective for the treatment of convulsant seizures, e.g. epileptic seizures.

The most familiar type of convulsant seizures are those associated with epilepsy, of which there are three distinct types—grand mal, petite mal and psychomotor seizures. Any one, or any combination, of these types of seizures may occur in epilepsy cases. A large number of these cases can be controlled with known anticonvulsant agents. However, in some cases, the so-called "refractory" cases, there is no completely effective therapy. As a consequence, the search has not ceased for new anticonvulsant agents.

It has now been found that convulsant seizures in white mice can be controlled or prevented by administering certain derivatives of thiosemicarbazides which have the following formula:

in which R is a member selected from the group consisting of:

Specific compounds which are useful in the method of the present invention are:

4-(2-methylbenzyl)-3-thiosemicarbazide,
4-(2,3-dimethylphenyl)-3-thiosemicarbazide,
4-(2,4-dimethylphenyl)-3-thiosemicarbazide, and
4-(2-ethylphenyl)-3-thiosemicarbazide.

The discovery that the above named thiosemicarbazide derivatives are effective as anticonvulsant agents is completely unexpected in view of the fact that all other thiosemicarbazide type compounds previously reported on are either known convulsants or have no central nervous system activity whatsoever. In no instance has the literature reported anticonvulsant efficacy for such other compounds. In view of the usefulness of the thiosemicarbazide derivatives of this invention in animals, these compounds hold very good promise as effective agents in the treatment of convulsant seizures in man.

The thiosemicarbazide derivatives that have been found useful in the present invention may be conveniently synthesized by the treatment of an appropriate isothiocyanate with hydrazine as illustrated in the following equation, although the invention is not limited to this specific method of preparation:

2

in which R is as previously defined.

The following examples further illustrate the syntheses of the thiosemicarbazide derivatives employed in the present invention and the use of these compounds in the treatment of convulsant seizures.

EXAMPLE I

4-(2,3-dimethylphenyl)-3-thiosemicarbazide

To a mixture of 5.0 ml. of 85% hydrazine hydrate in 50 ml. of methanol was added dropwise 8.2 g. (0.05 mole) of 2,3-dimethylphenyl isothiocyanate in 25 ml. of methanol. A solid formed as the mixture became heated by the exothermic reaction. The solid was collected on a filter and washed with petroleum ether. On recrystallization of the solid from alcohol, 6.9 g. of 4-(2,3-dimethylphenyl)-3-thiosemicarbazide was obtained in the form of a white solid having a melting point of 158–159° C.

EXAMPLE II

4-(2,4-dimethylphenyl)-3-thiosemicarbazide

The method of Example I was followed with the exception that 0.05 mole of 2,4-dimethylphenyl isothiocyanate was employed in place of the 2,3-dimethylphenyl isothiocyanate. Upon recrystallization from methanol, a yield of 7.4 g. of 4-(2,4-dimethylphenyl)-3-thiosemicarbazide was obtained in the form of a white solid which had a melting point of 150–152° C.

EXAMPLE III

4-(2-ethylphenyl)-3-thiosemicarbazide

To a mixture of 30 ml. of 85% hydrazine hydrate and 150 ml. of methanol was added dropwise with stirring, 16.3 g. (0.1 mole) of 2-ethylphenyl isothiocyanate in 50 ml. of methanol. The mixture was heated to 55° C. for 1 hour, and after cooling to room temperature, the solid was collected. After recrystallization from benzene with carbon treatment, a white solid was obtained. Upon drying, 12.4 g. of the compound was obtained, having a melting point of 129–131° C. The identity of the compound was confirmed as 4-(2-ethylphenyl)-3-thiosemicarbazide by elemental analysis as follows:

Calculated: carbon, 55.35%; hydrogen, 6.71%; sulfur, 16.42%. Found: carbon, 55.52%; hydrogen, 6.77%; sulfur, 16.49%.

EXAMPLE IV

4-(2-methylbenzyl)-3-thiosemicarbazide

To a mixture of 30 ml. of 85% hydrazine hydrate and 40 ml. of methanol was added dropwise with stirring, 16.3 g. (0.1 mole) of 2-methylbenzyl isothiocyanate in 40 ml. of methanol. The precipitate was collected and washed with petroleum ether. The crude material was recrystallized from methanol and then from butanol. Upon drying, 15.5 g. of 4-(2-methylbenzyl)-3-thiosemicarbazide in the form of a white solid was obtained having a melting point of 153–154° C.

The thiosemicarbazide derivatives are preferably employed in the method of the invention in the form of tablets, powders, capsules or other therapeutic dosage forms. In such forms the active anticonvulsant material may be admixed with a wide variety of pharmaceutical diluents which are not incompatible with the active ingredients. In these therapeutic dosage forms it is preferable to use at least about 10 mg. of the active compound per dose.

EXAMPLE V

In this example, the results of tests are reported in Table I, below, in which white mice were subjected to the established and conventional convulsant producing procedure known as electroshock. Anticonvulsant activity was

measured by means of the MES (maximal electroshock seizure pattern) described by Swinyard and co-workers, *J. Pharmacol. Exper. Therap.*, vol. 106, pp. 319-330 (1952). In this procedure the animal is subjected to electrical currents of the order of 40 milliamperes for about 0.2 second, the time of application of the electroshock coinciding with the peak effect of the medicament which is being given to the animal. Activity against electroshock is normally correlated with clinical efficacy against grand mal type epileptic seizures.

TABLE I

3-Thiosemicarbazide Derivative	AED ₅₀ MES. i.p.	ED ₅₀ MES. oral	ALD ₅₀ 7 day. i.p.	TD ₅₀ . oral
4-(2-methylbenzyl)-	9	12.5	250	53
4-(2,3-dimethylphenyl)-	10	34	500	168
4-(2,4-dimethylphenyl)-	11	21	300	107
4-(2-ethylphenyl)-	11	31	150	280

In the above table, one of the test parameters employed is the ED₅₀ which represents in milligrams the oral dose of the medicament per kilogram of body weight of the test animal, which when administered to the test animals will protect 50% of them from the effects of the electroshock. In determining the ED₅₀ at least ten animals are employed at each level for each compound being tested. Another test parameter reported in Table I is the AED₅₀ which is the approximate ED₅₀ obtained when the compound being tested is administered to the test animals intraperitoneally.

The above table also refers to the ALD₅₀ which is the Approximate Lethal Dose, which when given intraperitoneally will kill 50% of the test animals. The TD₅₀ referred to in the table is the amount of anticonvulsant material per kilogram of body weight which when administered orally will induce a toxic reaction in 50% of the animals.

From the data in Table I it is seen that the thiosemicarbazide derivatives of this invention have a pronounced activity in protecting the animals against the electroshock induced seizures which are generally recognized as corresponding to grand mal convulsant seizures. By way of comparison, the compound 4-phenyl thiosemicarbazide was convulsant to 50% of white mice given an oral dose at 29.5 mg./kg. and lethal to 50% of the mice at only 40 mg./kg. in the same test; the compound 4-methyl thiosemicarbazide was convulsant to 50% of white mice given an oral dose of 15.5 mg./kg.

The amount of the anticonvulsant material which would normally be administered is primarily determined by the physical characteristics of the recipient and severity of the convulsant seizures. Obviously, the amount of the particular compound to be administered must be an "effective amount," i.e., an amount which is medically beneficial but does not present toxic effects which outweigh the advantages which accompany its use. It would be expected that the adult human dosage would normally range upwardly from about 10 milligrams of the active compound. The exact dosage, of course, would depend on the physical characteristics of the recipient, the severity of the seizures and such other factors such as other medication. The dosage for other animals such as dogs would likewise be dependent upon a variety of factors and could to some extent be determined by trial testing.

As will be readily apparent to those skilled in the art, other examples of the herein-defined invention can be devised by various modifications, variations and adaptations without departing from the spirit and scope of the invention after reading the foregoing specification and the claims appended hereto. All such modifications, varia-

tions and adaptations are included within the scope of the invention as defined in the appended claims.

What we claim is:

1. The method of preventing convulsant seizures in animals which comprises administering to such animals an effective amount of a compound having the formula:

10 in which R is a member selected from the group consisting of:

15 and

20

2. The method of claim 1 in which the compound is 4-(2-methylbenzyl)-3-thiosemicarbazide.

3. The method of claim 1 in which the compound is

25 4-(2,3-dimethylphenyl)-3-thiosemicarbazide.

4. The method of claim 1 in which the compound is 4-(2,4-dimethylphenyl)-3-thiosemicarbazide.

5. The method of claim 1 in which the compound is

4-(2-ethylphenyl)-3-thiosemicarbazide.

30 6. A composition for preventing convulsant seizures in animals comprising at least 10 mg. of an active compound having the following formula:

35 in which R is a member selected from the group consisting of:

40 and

45

in combination with a pharmaceutical diluent in therapeutic dosage form selected from the group consisting of powders, tablets, and capsules.

50 7. The composition of matter of claim 6 in which the active compound is 4-(2-methylbenzyl)-3-thiosemicarbazide.

8. The composition of matter of claim 6 in which the active compound is 4-(2,3-dimethylphenyl)-3-thiosemicarbazide.

9. The composition of matter of claim 6 in which the active compound is 4-(2,4-dimethylphenyl)-2-thiosemicarbazide.

60 10. The composition of matter of claim 6 in which the active compound is 4-(2-ethylphenyl)-3-thiosemicarbazide.

11. 4-(2-ethylphenyl)-3-thiosemicarbazide.
